KICKOUT SASH

Harvey D. Carbiener and David L. Rutter, Elkhart, Ind., assignors to Excel Corporation, Elkhart, Ind., a corporation of Indiana

Application August 26, 1949, Serial No. 112,599

4 Claims. (Cl. 189—64)

1

This invention relates to window sash construction and particularly window sash constructions for busses, railway cars and the like, which sash frames are quickly removable in cases of emergency, without operating fastening means, by applying a sufficient force to overcome sash retaining devices, or to a window sash construction which may be called "knock-out" or "kick-out" sash.

More particularly it has for its object a knock-out, or kick-out, sash in which the sash frame is mounted by a force applied in a direction at a right angle to the sash to overcome the holding action of rigid cams acting inclined plane fashion, and also a sash which has a slight edgewise movement in one direction against a restraining resilient or spring action when the force is applied to overcome the holding action of the cams.

It further has for its object a sash frame with a sealing strip extending circumferentially around the edge of the same to coat with the window frame to make the sash weather tight, the sealing strip being yieldable when the sash is being knocked out. The sash is replaceable by the reverse of the movements taking place when the sash is being knocked out.

The invention consists in the novel features and in the combination and constructions hereinafter set forth and claimed.

In describing this invention, reference is had to the accompanying drawings in which like characters designate corresponding parts in all the views.

Figure 1 is an elevation, partly broken away, of a sash embodying this invention, contiguous portions of the window frame being also shown.

Figure 2 is an edge view looking to the left in Figure 1 of the sash frame, this being partly broken away and the contiguous portion of the window frame being also shown.

Figure 3 is an enlarged fragmentary side perspective projection looking to the left at the upper right hand corner of Figure 2.

Figures 4 and 5 are respectively fragmentary face and edge views of the lower rail of the sash frame showing the cam members thereon for coacting with complementary cam members on the sill plate of the window frame.

Figure 6 is an end view looking to the left in Figure 4.

Figures 7 and 8 are sectional views on lines 7—7 and 8—8, Figure 1.

This sash structure comprises a sash frame having cam means for interlocking with the window frame when being mounted in and dis-

2

lodged from the window frame when force is applied to the sash in a direction at an angle to the plane of the sash frame sufficient to overcome the holding action of the cam means. As here illustrated, the cam means is rigid with the sash and in order to permit the cam means to act inclined plane fashion, the entire sash frame has a shifting movement edge wise in one direction against the action of the returning spring also carried by the sash frame.

1 designates the sash frame, the stiles and rails of which are formed up of sheet metal of the contour shown in Figure 2.

2 designates window framing around the window opening in the car body. The sash frame 1 is provided with means for supporting glass panes. As here shown, two sub-sashes 3 and 4 are mounted in the main sash frame, one, as the lower sub-frame 3 being fixed, and the other or upper 4 being capable of being raised and lowered. It is provided with suitable sash locks 5 coacting with racks formed in the upper portions of the uprights or stiles of the sash frame 1. The sub-sash 4 is also provided with a lift handle 6 by which it may be closed, the sash holders ratcheting during the closing movement. The construction of the hub-sashes forms no part of this invention.

9 designates cams on an edge of the sash frame coacting with cams 10 on the confronting edge of the window frame, the sash having an edge-wise movement due to the cam action in one direction against resilient or spring means on the diametrically opposite edge of the sash frame.

35 In the sash here shown, the sash frame has a shifting movement vertically. The cams 9 are in the form of raised embossments on the edge of the lower rail of the sash frame 1, these coacting with the complementary cams or embossments 10 on the sill plate of the window frame 2.

40 When the sash is being placed in position, the embossments 9 cam up over the embossments 10 and shift the sash edgewise against the action of springs 11 on the edge of the upper rail of the sash frame, that is the edge of the sash frame diametrically opposite to the edge on which the cam members are located, these springs being secured to the upper rail and having arms pressing against the top rail of the window frame.

45 The opposite of this action takes place when sufficient force is applied to the sash to cause the cams 9 to ride over the cam 10 in dislodging the sash frame from the window frame. The sash frame is placed into position in the window frame 55 by a combined edgewise and pivotal movement,

the upper end of the sash frame 1 being here shown as held in position by pivots, the parts of which are detachable when the sash 1 is shifted upwardly by the cams and the sash swung outward. When swung outward, as seen in broken lines Figure 2, the springs may react to shift the sash downward and then the sash swung farther out on its pivotal axis, or the sash may be pushed upward against the springs and completely detached or unhooked from the window frame.

As here shown, the sash frame 1 is shown as formed with members as hooks 12 formed with slots 13 extending downwardly and open at their lower ends, which slots receive studs 14 on the window frame, the slots being located at the ends of the top rail of the sash frame 1 and the axis of the pivot being parallel to the upper edge of the sash 1. The members 12 thus serve to hold the sash at its upper end in the window frame. If desired, the hooks may be omitted and the sash frame 1 held in position by the cam means on one edge of the sash frame and flanges at the diametrically opposite edge to be first interlocked by holding the sash frame inclined outwardly, and then swinging the sash frame inwardly to allow the cams 9 and 10 to coat inclined plane fashion and shift the sash edgewise against the returning springs.

In order to seal the sash frame 1 in the window frame, or make the sash frame 1 weather tight, a continuous weather strip 15 of rubber, or the like, extends circumferentially entirely around the sash frame 1 and extends beyond the edge of the same and wipes at its outer edge on the window frame, it being here shown as seated in a groove 16 opening through the edge of the sash frame. As the sash frame is formed of sheet metal, this groove along the top rail forms a rib for coacting with the sealing strip 17 in a channel in the upper rail of the sub-sash 4. The stiles are formed with a similar groove which forms sash guides for the sub-sash 4. The bottom rail is formed with a similar groove 16.

By this construction, a quick, demountable, or knockout sash is provided which is economical to manufacture and readily adapted for safety purposes to the window openings of busses where egress of the passengers is possible in case of accidents and turn-overs where the doors are jammed, or obstructed.

What we claim is:

1. A knock-out window sash structure which comprises a rigid rectangular sash frame mountable in a window frame around a window opening, the sash frame having projecting cam means on the outer edge of one of the sash frame members coacting to ratchet inclined plane fashion and interlock and unlock with complementary cam means projecting from the confronting inner face of the window frame, the sash frame being mounted to have a limited edgewise shifting movement in the window frame under the ratcheting action of the cam means, and spring means between the sash frame member and the window frame to resist the edgewise movement.

2. A knock-out window sash structure which comprises a rigid rectangular sash frame mountable in a window frame around a window opening, the sash frame having projecting cam means on the outer edge of one of the sash frame members coacting to ratchet inclined plane fashion and interlock and unlock with complementary

cam means projecting from the confronting inner face of the window frame, the sash frame being mounted to have a limited edgewise shifting movement in the window frame under the ratcheting action of the cam means, spring means between the sash frame member and the window frame to resist the edgewise movement, and a flexible sealing strip secured to the rigid sash frame extending circumferentially around the same and located to coact with the opposing inner face of the window frame.

3. A knock-out window sash structure which comprises a rigid rectangular sash frame mountable in a window frame around a window opening, the sash frame having projecting cam means on the outer edge of one of the sash frame members coacting to ratchet inclined plane fashion and interlock and unlock with complementary cam means projecting from the confronting inner face of the window frame, the sash frame being mounted to have a limited edgewise shifting movement in the window frame under the ratcheting action of the cam means, spring means between the sash frame member and the window frame to resist the edgewise movement, and a pivotal connection between the sash frame and the window frame located near the edge of the sash frame opposite to that on which the cam means are located, the pivotal connection being also located with its axis parallel to the edge of the sash frame member on which the cam means are located.

4. A knock-out window sash structure which comprises a rigid rectangular sash frame mountable in a window frame around a window opening, the sash frame having projecting cam means on the outer edge of one of the sash frame members coacting to ratchet inclined plane fashion and interlock and unlock with complementary cams on the confronting inner face of the window frame, the sash frame being mounted to have a limited edgewise shifting movement in the window frame under the ratcheting action of the cam means, spring means between the sash frame member and the window frame to resist the edgewise movement, and a pivotal connection between the sash frame and the window frame located near the edge of the sash frame opposite to that on which the cam means are located, the pivotal connection being also located with its axis parallel to the edge of the sash frame member on which the cam means are located, the pivotal connection comprising parts on the sash frame formed with slots extending towards the edge of the sash provided with the cam means, the slots being open at their ends toward the edge on which the cam means are located, and studs on the window frame extending into the slots, whereby the sash frame is disengaged from the studs upon shifting of the sash frame edgewise by the cam means.
